UNITED STATES PATENT OFFICE.

JOHN B. PRUDEN, OF QUANAH, TEXAS.

CUT-OFF.

1,018,925.

Specification of Letters Patent. Patented Feb. 27, 1912.

Application filed June 1, 1911. Serial No. 630,550.

To all whom it may concern:

Be it known that I, JOHN B. PRUDEN, a citizen of the United States, and a resident of Quanah, in the county of Hardeman and 5 State of Texas, have invented certain new and useful Improvements in Cut-Offs, of which the following is a specification.

This invention is an improvement in cut-offs for water pipes, having for an object to 10 provide a novel construction to control the supply of water discharged from a roof so that a given amount of the water may be conducted to a sewer or other off-take until 15 the roof has been washed, and the balance of the water be deflected into a cistern or other reservoir; and the invention consists in certain novel constructions and combinations of parts as will be hereinafter described and claimed.

20 In the drawing Figure 1 is a vertical longitudinal section and Fig. 2 is a front elevation, partly in section, of a cut-off embodying my invention. Fig. 3 is a side elevation of a portion of the apparatus. Fig. 25 4 is a cross section on about line 4—4 of Fig. 3.

In carrying out the invention, the water pipe A has a branch B and a valve C is pivoted at C' and may be adjusted to the full 30 line position shown in Fig. 1 to permit the water to pass down through the pipe A, or to the dotted line position indicated in Fig. 1, to deflect the water through the branch B. To this valve is fixed a depending lever C² 35 by which the valve may be operated and a weight C³, connected with the valve, operates to adjust the valve automatically to the dotted line position shown in Fig. 1, when the lever C² is released by the detent mechanism presently described. This detent 40 mechanism includes a catch D pivoted at D' and having an arm D² with a seat D³ to engage the pin C⁴ at the end of the lever C² and the lever D² has a handle extension D⁴ 45 beyond the seat D³ for convenience in manipulating the said lever. The catch D also has a bail-shaped portion D⁵ provided with an arm D⁶ engaging with the edge of a mutilated wheel E in a train of gears F

driven by a water wheel G, whose blades G' 50 are operated upon by the water passing through the water pipe. The wheel E has a notch E' into which the pin D' on the arm D⁶ may pass to permit the catch D to drop and release the lever C² when the said pin 55 D' registers with the notch E' as the wheel E is revolved. The wheel E is connected by a ratchet H with its wheel I of the train F, so that in setting the valve the wheel can be readily turned back to the desired position 60 for setting the wheel for a new operation.

If desired, the wheel G may be set a little farther back or to the left from the position shown in Fig. 1 to let the water hit the blades a little farther from the pivotal center G² of the wheel. 65

In the operation of the invention, when the parts are as shown in full lines in Fig. 1, in case of a shower, the water will pass from the roof down the pipe A and will act 70 on the wheel G to revolve the same and this through the train F will turn the mutilated wheel until the notch E' comes into position to permit the passage of the pin D' into the said notch when the catch will drop from 75 the full line position shown in Fig. 1, releasing the lever C² from engagement with the seat D³ so the weight C³ can tilt the valve to the dotted line position shown in Fig. 1, when the balance of water will pass 80 through the branch B into the cistern or other receiver.

In practice, it is preferred to inclose the train with the removable casing J, as shown in Figs. 2 and 3 of the drawing. 85

I claim:

The improvement herein described comprising a pipe having a branch, a valve pivoted at the juncture of the pipe and branch and adapted to shut off the branch or to be 90 adjusted across the pipe to deflect water out through the branch, a weight for operating the valve in one direction, a lever projecting from the valve, a pivoted catch having an outwardly projecting arm provided with 95 a seat for engagement with the valve lever to secure the valve in one position, said arm having a handle extension, and the catch

having a bail-shaped portion, a water wheel operating in the water pipe, a train operated by said water wheel and a mutilated wheel having a ratchet connection with the 5 train and provided with a notch, the bail-shaped portion being provided with an arm which may project into said notch to release

the catch, all substantially as and for the purposes set forth.

JOHN B. PRUDEN.
